UNITED STATES PATENT OFFICE.

LEWIS C. McALLISTER, OF FORT WORTH, TEXAS.

SEWING-MACHINE.

SPECIFICATION forming part of Letters Patent No. 278,809, dated June 5, 1883.

Application filed July 31, 1882. (No model.)

To all whom it may concern:

Be it known that I, L. C. McALLISTER, a citizen of the United States, residing at Fort Worth, in the county of Tarrant and State of Texas, have invented certain new and useful Improvements in Sewing-Machines, of which the following is a specification, reference being had therein to the accompanying drawings.

This invention relates to improvements in that class of sewing-machines wherein the shuttle rotates instead of reciprocating; and it consists in the arrangement and construction of the shuttle, bobbin, and shuttle-thread controller, whereby the shuttle-thread at a certain time in each revolution of the shuttle is rewound upon the bobbin, which prevents the thread from twisting or untwisting, all of which will be more particularly described hereinafter, and set forth in the claims.

In the drawings, Figure 1 is a plan view of a sewing-machine with the bed-plate removed to show the parts of the machine below it. Fig. 2 is a vertical projection on line xx of Fig. 1. Fig. 3 is a vertical projection on line yy of Fig. 1. Fig. 4 represents, in four diagrams, a modification of the thread - controller as shown in Fig. 1, to show the relative positions of the needle, the thread-controller, and the shuttle giving off the thread from the bobbin. Figs. 5 and 7 are different views of the shuttle and bobbin. Fig. 6 is an elevation of a sewing-machine, partly in section, showing the manner of operating the shuttle-shaft. Fig. 8 is an enlarged section of the bobbin and spring tension-bar. Fig. 9 is a perspective view of the shuttle holder or carrier.

A^2 represent the frame of any ordinary sewing-machine. In Fig. 1 the plate is removed, leaving a portion, A' , where the needle passes through.

A^2 in Fig. 1 is a cross-bearer, in which one end of the shaft B is sustained. It is understood that this shaft B may be supported in any convenient manner beneath the plate, so that its center is on a line with the center around which is the shuttle-race. Near the outer end of shaft B there is a crank, B^3 , and wrist b^3 , Fig. 6, to which is coupled the connecting-rod H' , which operates the needle-bar shaft I .

On shaft B is the driving-pulley B' , receiving motion, as usual, by a band from the driving-wheel. It is understood that this shaft B may be driven by various other means as well as by that herein described. 55

B' on shaft B is an eccentric cam having an eccentric-rod, b , which is connected to the arm C' of a rocking shaft, C , which is properly supported in the frame beneath the plate.

On the shaft C there is an arm, C^2 , and attached to it by a joint is a rod, D , which passes across the frame and above the shaft B . On this rod D is an arm, d , at the end of which is a hook, d' . This I call a "thread-controller," as it takes up the slack thread and prevents it from twisting. This rod D passes through a bearing at d' , sliding through it to and fro. 60

On shaft B , at its inner end, there is a crank, B^3 , which is on one side of the center of shaft B and secured to it. To this crank B^3 is attached the shuttle-carrier E , which is of any convenient form, and in which rests the shuttle which is seen in Fig. 5. F is the shuttle-race, as represented in front views in Fig. 4. In the carrier E there is a spring, e , the function 70 of which is to press the shuttle against the race F , and also to assist in keeping the bobbin in the shuttle. In Figs. 5, 7, and 8 are shown the sections of the shuttle and the means for supporting the bobbin within the shuttle, 75 and the spring by which the tension on the bobbin is given or regulated, and at the same time serves to keep the bobbin from moving endwise, as by this movement endwise the bobbin would obstruct the upper thread when 80 passing over the shuttle.

G is a flat plate, to which is hinged the hollow cover G' . On plate G is a solid pin, g , and in the bobbin H there is a hollow spindle, h , which fits over pin g . The upper plate, h' , of H is a solid 90 disk. The lower plate, h^2 , fits around the hollow spindle h . When the bobbin H , with its complement of thread, which should not be too full, is to be placed on the pin g , the spring g^2 and plate g' should be pressed back, and when 95 the bobbin H is down the plate g' will be caused by the spring g^2 to press against the thread, on the bobbin continuously. The cover G' is pressed down upon the plate G , and is held as the case of a watch is held, and is easily re- 100

moved when a new bobbin is to be put in. The fastening of the shuttle-carrier to the crank B³ is made in any convenient and suitable manner for quick removal and replacing of a new 5 bobbin when it is to be put in.

- It is to be observed that when the bobbin is full the spring g² is compressed to its fullest extent, and the tension on the bobbin is at its maximum, and as the thread is used off the 10 piece tension becomes gradually less. This is a compensating medium, for as the diameter of the thread on the bobbin is diminished the thread is tightened, because the bobbin has to revolve oftener to deliver a given quantity of thread.
- 15 The thread-controller d also assists in the tension of the thread on the bobbin. In place of the coiled spring, a flat spring may be used, and an adjusting-screw may be put in the piece g³, which acts as a guide to the spring-stem.
- 20 Various methods may be used to press upon the thread as it diminishes upon the bobbin. It will be noticed that one end of the bobbin is closed, which insures the bobbin being always placed on the pin as it should be, that 25 25 the thread will certainly unwind in the proper direction, as, when the thread-controller operates, the thread is carried back upon the shuttle, as will be explained.

In Fig. 4 are four diagrams representing an 30 inside face view of the shuttle-race and a modification of the thread-controller, as shown and described in Fig. 1. The rod D, instead of passing across the main shaft and having a projecting hooked arm, d d', can be a rod with 35 a hooked end, d', and, as shown in No. 4 of Fig. 4, be attached to the arm C² of a rocker-shaft, C, on the rear side of the frame, when the hooked end d' will pull the thread instead of shoving it, as in Fig. 1, the operation upon 40 the thread being precisely the same in both cases, as follows, viz:

When the shuttle is at the point represented at No. 1 in Fig. 4, the thread comes from the bobbin upward, and the thread-controller d 45 has carried it to the right or rear of the bed-plate A', the shuttle is about to pass to the left and through the loop of the upper thread, the needle being down and having formed said loop. In No. 2 the shuttle has passed through 50 the loop to the left or front of the bed-plate A', and the thread-controller d has also passed to the left or front, and the needle is above the bed-plate A', ascending. At No. 3 the shuttle 55 is at its lowest point and the thread-controller d is just beginning to move to the right or rear,

carrying with it the shuttle-thread, and the needle is at its highest point, ready to descend. In No. 4 the shuttle is rising and the thread-controller d is passing to the right or rear with the slack thread from the shuttle, and the needle is descending, ready to take its position, as 60 in No. 1, when the shuttle shall have also gained its position there. In doing this the shuttle has made one revolution and formed the stitch by carrying the bobbin through the 65 loop of the upper thread, the thread has been given off from the bobbin on the side opposite to the needle and carried back upon the bobbin just about the time the point of the shuttle enters the loop of the upper thread, and 70 the bobbin has unwound itself in a direction opposite to that traveled by the shuttle, and all tendency of the thread to twist has been counteracted by the thread having been kept tight and rewound onto the bobbin by the 75 thread-controller.

So far as I know, I am the first to use a thread-controller to aid in rewinding the shuttle-thread on the bobbin, which rewinding prevents the shuttle-thread from being twisted or untwisted, 80 and this feature I claim, and do not confine myself, primarily, to the use of the particular reciprocating thread-controller shown, that being only one practical form of my invention.

I claim—

1. In a rotary-shuttle sewing-machine, a shuttle-thread controller to aid in rewinding the slack thread upon the bobbin, substantially as and for the purpose described. 85
2. The combination of the rocker-shaft C 90 and arm C², the rod D, and thread-controller d, substantially as and for the purpose described.
3. In a sewing-machine shuttle having one end of the bobbin exposed, a tension-spring 95 to press against the thread of the bobbin, near the inner plate, and arranged to follow the thread toward the spindle as the thread is used off the bobbin, and also to press against the inner plate of the bobbin, to prevent the bobbin from moving endwise toward its exposed 100 end, leaving a sufficient space between the spring and the exposed end of the bobbin for rewinding the thread thereon, substantially as and for the purpose described.

In testimony whereof I affix my signature in 105 presence of two witnesses.

LEWIS C. McALLISTER.
